(57) **CLAIM**

I claim the ornamental design for a landscaping tool, as shown and described.

DESCRIPTION

FIG. 1 is a perspective side view of the frame for a landscaping tool according to the design.

FIG. 2 is a planar side view of the design;

FIG. 3 is a planar front view of the design;

FIG. 4 is a planar rear view of the design;

FIG. 5 is a planar top view of the design; and,

FIG. 6 is a planar bottom view of the design.

The broken line depiction of the tool head is for the purpose of showing portions of the article and forms no part of the claimed design.
